(57) **CLAIM**

The ornamental design for a toy ball, as shown and described.

DESCRIPTION

FIG. 1 is a first perspective view of a toy ball showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1;

FIG. 11 is an enlarged view of the selected portion 11 in FIG. 1;

FIG. 12 is an enlarged view of the selected portion 12 in FIG. 2;

FIG. 13 is an enlarged view of the selected portion 13 in FIG. 2; and,

FIG. 14 is an enlarged view of the selected portion 14 in FIG. 2.

The evenly broken lines disclose unclaimed portions of the toy ball; the dash-dot broken lines disclose boundaries of the isolated and partial views; the broken lines in the drawings form no part of the claimed design.

1 Claim, 14 Drawing Sheets
